UNITED STATES PATENT OFFICE

ERICH NOACK, OF WIESDORF-ON-THE-RHINE, OSWIN NITZSCHKE, OF LEVERKUSEN-ON-THE-RHINE, AND GEORG PFLEIDERER, OF LUDWIGSHAFEN-ON-THE-RHINE, GERMANY, ASSIGNORS TO I. G. FARBENINDUSTRIE AKTIENGESELLSCHAFT, OF FRANKFORT-ON-THE-MAIN, GERMANY, A CORPORATION OF GERMANY

ELECTROLYTICAL MANUFACTURE OF COMPOUNDS CONTAINING ACTIVE OXYGEN

Application filed June 21, 1928, Serial No. 287,348, and in Germany July 11, 1927.

The present invention concerns the electrolytical manufacture of compounds containing active oxygen in which the amalgamated cathodes employed are wetted by mercury.

5 In the electrolytic production of compounds containing active oxygen, for instance hydrogen peroxide, corrosion of the amalgamated cathodes sometimes occurs.

10 In accordance with the present invention this risk can be effectively reduced by frequent or continuous wetting of the cathodes with fresh mercury during the electrolysis. For example, this wetting can be effected by causing mercury to trickle over the cathodes.

15 The surface of the mercury flowing from the cathode can be protected from attack by the liquid in the cell by being permanently kept cathodically polarized. Conveniently the excess mercury runs away through a siphon-like outlet, which is blocked to the electrolytes by the mercury. Instead of trickling metallic mercury over the cathodes small quantities of mercury salts may be added to the electrolytes entering the cathode chamber. Since the deposition potential of mercury is essentially lower than the reduction potential of molecular oxygen, the metal is deposited completely and uniformly on the cathode, this indeed without any considerable expenditure of current due to the high equivalent weight of mercury.

20 The accompanying drawing shows a representation of an electrolyzing vessel, in which 1 means a distributing device from which the mercury is trickled over the cathode 2. The mercury flows away through a siphon-like outlet 3 and is pumped back by the pump 4 to the distributor 1. Figure 5 means the anode and 6 the diaphragm.

25 We claim:

1. In the process for the electrolytic manufacture of compounds containing active oxygen, the step which comprises wetting the amalgamated cathodes employed with mercury during the electrolysis.

2. In the process for the electrolytic manufacture of compounds containing active oxygen, the step which comprises wetting the amalgamated cathodes employed with mer-

cury during the electrolysis; whereby the wetting is effected by the electrolytic deposition of mercury on the cathodes.

3. In the process for the electrolytic manufacture of hydrogen peroxide, the step which comprises wetting the amalgamated cathodes employed with mercury during the electrolysis.

4. In the process for the electrolytic manufacture of hydrogen peroxide, the step which comprises wetting the amalgamated cathodes employed with mercury during the electrolysis; whereby the wetting is effected by the electrolytic deposition of mercury on the cathodes.

5 In testimony whereof we have hereunto set our hands.
